UNITED STATES PATENT OFFICE

2,562,731

NOZZLE ASSEMBLY

Thomas W. Murphy, Narberth, Pa., assignor to
Monarch Manufacturing Works, Inc., Philadelphia, Pa., a corporation of Delaware

Application January 4, 1946, Serial No. 639,030

6 Claims. (Cl. 299—120)

1

This invention relates to an improvement in spray nozzle assemblies, and specifically to means for more accurately and uniformly seating the terminal member in the tip of the nozzle.

One of the objects of this invention is the provision of means for more perfectly seating the terminal member accurately with relation to the rear of the orifice in the tip when securing the terminal member in the tip by means of a securing nut or member.

Another object of my invention is the provision of means between the terminal member and securing nut or member, which will permit perfect centering of the terminal member with respect to the angular seat in the tip.

These and other objects of the invention will become apparent from the accompanying drawings, in which:

Fig. 1 is a sectional view through a nozzle showing one form of assembly in accordance with my invention;

Fig. 2 is a partial sectional view through another form of terminal member securing means;

Fig. 3 is a view similar to Fig. 2 showing another form of terminal member securing means; and

Fig. 4 is a plan view of a terminal member.

In the drawings the body or adapter A is internally screw threaded at 10, for connecting the nozzle to a liquid supply, and also has internal threads at 12 in which is threaded a tip B having a flange 14 in contact with the end of the body A. The periphery of the flange 14 may be knurled or shaped for engagement with a wrench for screwing the tip into the body.

The tip B is provided with the usual orifice 16, and a conical seat 18, converging from the bore 20 in the tip to the orifice 16.

Seated against the conical surface 18 in the tip is a terminal member C, the angle of the seating surface 22 of which corresponds to the seating surface 18 in the tip B, and which is adapted to be seated centrally relative to the orifice 16 in the tip B.

The terminal member C, in Fig. 1, is retained in position by a lock-nut D, in threaded engagement with threads 24 in the bore 20 of the tip B, and is provided with a slot 26 for the reception of a tool for screwing the nut D inwardly to force the terminal member against its seat.

In Fig. 1, the terminal member C, is provided with a stem 28 located in the bore of a spacer E between the terminal member C and a ball F seated in a socket in spacer E and a socket in the lock-nut D, whereby a universal pivoted joint is provided between the terminal member C and the nut D, to insure an accurate and tight seating of the terminal member on the seat 18 in the tip B, and concentrically with the orifice 16 in the tip. In order to provide equal pressures

2

within and without the spacer E, openings 29 are formed in the wall of the spacer.

Threaded in the bore 20 of the tip B, is a strainer support G, which is provided with a knurled flange 28, on which is supported a gauze strainer 30, for straining the liquid passing through the nozzle.

The liquid passing through the nozzle enters the opening in the end of the body A into a chamber a, then through the strainer 30 and, openings 32 in the strainer support into a chamber g in the strainer support G, then through feed slots 34 in the lock-nut D into a chamber b in the tip B, then through tangential slots 36 in the terminal member into a whirl chamber between the upper end of the terminal member C and the wall of the tip B, and then out through orifice 16 in a conical spray, due to the tangentially directed slots 28 in the terminal member.

As the seating surfaces on the tip B and the terminal member C are at the same angle, and as there is a universal pivotal connection between the terminal member C and the lock-nut D, the terminal member C will be centrally seated with relation of the orifice 16 and the conical seat 18 in the tip B, even though the axis of one or more of the several members should be angularly misaligned with other members as assembly occurs, whereby a tight seal is maintained at all portions of seating surface 22 of the terminal member C, except the portions through which the slots 36 are formed, so that the whirling of the liquid in the whirl chamber 38, caused by the flow through slots 36, will not be disrupted by leakage thereto from chamber b due to an incorrect positioning of the terminal member C with relation to the tip B and so that the whirl chamber itself is concentric with the orifice to provide a symmetrical spray.

In Fig. 2, I have shown another means, for providing a universal pivotal connection between the terminal member C², and the lock-nut D², in which the lock-nut D², is provided with a spherically shaped head portion 50, seated in a socket in the lower end of the spacer E².

In this form the liquid passes up through passage 34², into the interior of the spacer and out through feed hole 29². The terminal member C², is provided with tangential slots 36², and a stem 28². The lock-nut D² is provided with the usual tool engaging slot 26².

In the form shown in Fig. 3, the same reference characters have been applied to the same elements as in Fig. 1, with the numeral 3 affixed, and in which the spacer E³ is provided with a spherically shaped end portion 52 seated in a socket in the face of the lock-nut D³.

It will readily be appreciated that the terminal member and the spacer may be formed in a single piece, with a spherically shaped end portion

to seat in a socket in the lock-nut, or with a socket for the reception of a spherically shaped member on the lock-nut.

It will be evident that numerous variations of the details of construction may be made, without departing from the spirit and scope of the invention as defined in the appended claims.

The advantages of my invention result from the provision of means between the terminal member and the lock-nut, whereby the terminal member is accurately and uniformly seated in the seat in the tip, to prevent leakage between the engaging portions of the terminal member and the tip, and to perfectly align the terminal and tip, whereby disturbance to the whirling of the liquid in the whirl chamber, caused by jets delivered to the whirl chamber, is prevented.

What I desire to secure by Letters Patent is:

1. A nozzle comprising a hollow tip, a discharge orifice in said tip and a seat in said tip surrounding said orifice, a terminal member, said terminal member having a surface for engagement with the seat in said tip and being provided with slots in said surface for the passage of liquid to said discharge orifice, means, including a locking nut threaded into said tip and a substantially spherically shaped surface and a seat therefor permitting swiveling movement between said terminal member and said nut, for holding said terminal member with said surface in contact with said seat and providing proper angular alignment and sealing engagement between said surface and said seat, and means for admitting liquid to the outer ends of said terminal member slots.

2. A nozzle comprising a hollow tip, a discharge orifice in said tip and a seat in said tip surrounding said orifice, a terminal member, said terminal member having a surface for engagement with the seat in said tip, there being a swirl chamber between the tip and the terminal member communicating with the discharge orifice and slots in said surface of the terminal member tangentially arranged with respect to the swirl chamber, means, including a locking nut threaded into said tip and a substantially spherically shaped surface and a seat therefor permitting swiveling movement between said terminal member and said nut, for holding said terminal member with said surface in contact with said seat and providing proper angular alignment and sealing engagement between said surface and said seat, and means for admitting liquid to the outer ends of said terminal member slots.

3. A nozzle comprising a hollow tip, a discharge orifice in said tip and a seat in said tip surrounding said orifice, a terminal member, said terminal member having a surface for engagement with the seat in said tip, there being a swirl chamber between the tip and the terminal member communicating with the discharge orifice and slots in said surface of the terminal member tangentially arranged with respect to the swirl chamber, means, including a locking nut threaded into said tip and a substantially spherically shaped element and a seat therefor permitting swiveling movement between said terminal member and said nut, for holding said terminal member with said surface in contact with said seat and providing proper angular alignment and sealing engagement between said surface and said seat, and means for admitting liquid to the outer ends of said terminal member slots.

4. A nozzle comprising a hollow tip, a discharge orifice in said tip and a conical seat in said tip surrounding said orifice, a terminal member, said terminal member having a surface for engagement with the seat in said tip, there being a swirl chamber between the tip and the terminal member communicating with the discharge orifice and slots in said surface of the terminal member tangentially arranged with respect to the swirl chamber, means, including a locking nut threaded into said tip and a substantially spherically shaped surface and a seat therefor permitting swiveling movement between said terminal member and said nut, for holding said terminal member with said surface in contact with said seat and providing proper angular alignment and sealing engagement between said surface and said seat, and means for admitting liquid to the outer ends of said terminal member slots.

5. A nozzle comprising a hollow tip, a discharge orifice in said tip and a conical seat in said tip surrounding said orifice, a terminal member, said terminal member having a surface for engagement with the seat in said tip, there being a swirl chamber between the tip and the terminal member communicating with the discharge orifice and slots in said surface of the terminal member tangentially arranged with respect to the swirl chamber, means, including a locking nut threaded into said tip and a substantially spherically shaped element and a seat therefor permitting swiveling movement between said terminal member and said nut, for holding said terminal member with said surface in contact with said seat and providing proper angular alignment and sealing engagement between said surface and said seat, and means for admitting liquid to the outer ends of said terminal member slots.

6. A nozzle comprising a hollow tip, a discharge orifice in said tip and a seat in said tip surrounding said orifice, a terminal member, said terminal member having a surface for engagement with the seat in said tip and being provided with slots in said surface for the passage of liquid to said discharge orifice, means, including a locking nut threaded into said tip and a substantially spherically shaped surface carried by said locking nut and a seat therefor permitting swiveling movement between said terminal member and said nut, for holding said terminal member with said surface in contact with said seat and providing proper angular alignment and sealing engagement between said surface and said seat, and means for admitting liquid to the outer ends of said terminal member slots.
